WATER TROUGH FOR FOWL

John Ludi, Toms River, N. J.

Application December 17, 1954, Serial No. 33,601

Term of patent 14 years

(Cl. D12—2)

Figure 1 is a top plan view of a water trough for fowl illustrating my new design.

Figure 2 is a side elevational view of the same.

Figure 3 is an end elevation of the trough.

Figure 4 is a transverse cross-sectional view taken on the vertical plane of line 4—4 of Figure 1, looking in the direction of the arrows.

The appearance of the undisclosed side of the water trough is substantially the same as the side shown.

I claim:

The ornamental design for a water trough for fowl, as shown and described.
